DISPLAY STAND BASE

James E. Culver, Chicago, Ill.

Application February 9, 1948, Serial No. 7,159

2 Claims. (Cl. 248—226)

1

This invention relates to new and useful improvements in display stand bases and the primary object of the present invention is to provide a supporting frame that is quickly and readily applied to or removed from a supporting structure to engage display signs or posters in a convenient manner.

Another important object of the present invention is to provide a display stand base including an indicia supporting frame and novel and improved means for attaching the frame to supporting structures of various heights or depths.

A further object of the present invention is to provide a display stand base that is extremely small and compact in structure and which is conveniently assembled or disassembled facilitating the shipping or storing of the same.

A still further aim of the present invention is to provide a display stand base that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a perspective view showing the present invention applied to a freezing compartment;

Figure 2 is a fragmentary sectional view taken substantially on the plane of section line 2—2 of Figure 1;

Figure 3 is a fragmentary side elevational view of one upright of the present invention and showing the means for the attaching of the same to a supporting structure (in part); and,

Figure 4 is a perspective view of one of the base members used in conjunction with the present invention.

Referring now to the drawing in detail, wherein for the purpose of illustration, there is disclosed a preferred embodiment of the present invention, the numeral 10 represents the supporting frame used in conjunction with the present display stand base generally including a pair of spaced uprights 12 the lower ends of which threadingly engage nuts 13 and the upper ends of which support elbow joints or the like 14 that engage the ends of an upper rail 16.

Slidably engaging the uprights 12 are apertures 18 provided in substantially L-shaped or angulated base members 20 the shorter legs 22 of

which frictionally engage the uprights 12. Integrally formed with the base members 20, are gripping ribs 24 that frictionally engage the lower wall of a supporting structure such as a freezing unit or the like 26.

The numeral 28 represents a pair of bearing members or plates one of which cooperates with each of the base members 20. Rigidly secured to or forming an integral part of the bearing members 28, are split sleeves 30 that are adjustably connected by bolts and nuts 32.

In practical use of the present invention, the base members 20 frictionally engage the lower wall of the freezing unit or the like 26, the ribs 24 enter recesses R in the lower wall, and the sleeves 30 are adjusted on the uprights 12 so that the bearing members 28 frictionally engage the upper wall of the freezing unit or the like 26 to retain the uprights 12 in a substantially vertical position so that indicia bearing signs may be conveniently hung from the upper rail 16.

In view of the foregoing description taken in conjunction with the accompanying drawing it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

- 35 1. For use with an ice cream freezer including an upper wall and a pair of side walls having recessed portions adjacent their lower ends constituting bearing shoulders; a display attachment 40 for the ice cream freezer, said attachment comprising a supporting frame including a pair of uprights and a substantially horizontal rail terminally secured to said uprights, a pair of substantially L-shaped base members having apertures 45 in their longer legs slidably receiving said uprights, the shorter legs of said L-shaped base members bearing against said uprights to retain the longer legs of said L-shaped base members perpendicular to said uprights, the lower ends of 50 said uprights being threaded, nuts received on the threaded lower ends of said uprights and forming supports for said L-shaped base members, ribs on the longer legs of said L-shaped base members adapted to be received in depressions in the bearing shoulders to restrict lateral

movement of the uprights, and bearing members slidably and adjustably received on said uprights and having flat surfaces for bearing upon the upper wall of the freezer.

2. In an ice cream freezer including upper and lower portions and recesses provided in said lower portion; a display attachment comprising a pair of uprights, a rail joining the uprights, a pair of base members carried by said uprights, ribs on said base members received in said recesses to prevent lateral movement of said uprights relative to said freezer, and a pair of bearing members slidably and adjustably received on said uprights and resting upon the upper portion of said freezer.
